UNITED STATES PATENT OFFICE.

CLARE MACDONALD SUPPLE, OF BOSTON, MASSACHUSETTS.

STOCKING-SUPPORTER.

1,353,671.

Specification of Letters Patent. Patented Sept. 21, 1920.

Application filed April 2, 1920. Serial No. 370,764.

To all whom it may concern:

Be it known that I, CLARE MACDONALD SUPPLE, a citizen of the United States, residing at Boston, in the county of Suffolk and State of Massachusetts, have invented new and useful Improvements in Stocking-Supporters, of which the following is a specification.

The object of my present invention is the provision of a stocking supporter designed to be attached to a corset and constructed in a simple and inexpensive manner with a view to being expeditiously and easily applied in such manner that the stocking is safely and comfortably supported and yet there is no liability whatever of the stocking being cut or torn about the knee portion thereof.

To the attainment of the foregoing, the invention consists in the improvement as hereinafter described and definitely claimed.

In the accompanying drawing, hereby made a part hereof:

The figure is an elevation of my novel stocking supporter as the same appears precedent to use.

My novel stocking supporter is in the nature of an article of manufacture and includes among other elements two sections 1 and 1^a, preferably of thin and soft textile material. Each of the said sections 1 and 1^a is provided with an upwardly tapered and truncated upper portion as illustrated. Extending between and permanently joined in appropriate manner to the opposed ends of the lower portions of the spaced sections 1 and 1^a is an elastic section 2, and permanently joined to and extending from the opposite end of the lower portion of the section 1^a is an elastic strap 3. Connected in permanent manner to the outer end of the lower portion of the section 1 is a strong tape section 4, and carried by said tape section 4 is a buckle 5, which *per se*, is not of my invention. I would therefore have it understood at this point that any appropriate buckle 5 that is compatible with the purpose of my invention may be employed at the point stated on the tape section 4.

In addition to the elements named, the supporter comprises elastic sections 6 permanently joined to and extending upwardly from the upper ends of the sections 1 and 1^a, and links 7 carried by the said elastic sections 6 and designed to be connected through

the medium of the usual pendent tabs (not shown) to a corset; it being understood in this connection that the said tabs are carried by and form appurtenances of the corset, and that, therefore, when properly applied, my novel supporter will have the capacity of supporting a stocking and at the same time holding the corset against upward movement from its proper position. I prefer to provide one of the elastic sections 6 with a lateral sub-section 8, carrying a fastener 9; this, however, is not of the essence of my invention, and it is therefore to be understood that the sub-section 8 may be either employed or altogether omitted without affecting my claimed invention.

In the practical use of my novel stocking supporter, the same is placed about the knee portion of the stocking at a point immediately below the knee, and so that the sections 1 and 1^a rest at opposite sides of the knee, the elastic section 2 rests back of the knee, and the elastic strap 3 is connected to the buckle 5 in front of the side of the knee. This latter arrangement manifestly makes it very convenient to apply and adjust and fasten the supporter in its working position. It will also be noted that the tape section 4 and the elastic strap 3 prevent the buckle from contacting with the stocking or the like. The arrangement described of my novel supporter is advantageous because when the wearer is in a standing position, the muscles in the back of the lower leg at the knee contract, with the result that the circumference of the leg at that point is increased. The elastic section 2 affords ample expansion at the said point to conduce to the comfort of the wearer. Again when the wearer is in a sitting or kneeling position and the knee is thrown forwardly the circumference in front of the leg below the knee is engaged, but this enlargement is comfortably compensated for by the elasticity of the strap section 3. The sections 1 and 1^a assume positions at either side of the knee, and both are likely to retain their positions because of the capacity of the sections 2 and 3 to expand and contract comfortably to the movements of the leg. Moreover the said sections 1 and 1^a serve to brace and prevent undue lateral motion of the knee joint, which is particularly true when high heel boots are worn.

Manifestly my novel supporter may be

worn loosely or may be made very tight about the leg below the knee, as desired by the wearer. The subsection 8 and its appurtenances are employed to hold the upper part of the stocking as high as possible on the leg and preclude the said upper part falling over the knee.

Having described my invention, what I claim and desire to secure by Letters-Patent, is:

1. As a new and useful article of manufacture, a stocking supporter adapted to be worn about the stocking below the knee of the wearer, and including two spaced textile sections with upwardly tapered and truncated upper portions, an elastic section interposed between and permanently connecting the adjacent ends of the lower portions of the textile sections, an elastic strap permanently joined to the outer end of the lower portion of one textile section, a buckle connected through a tape section with the outer end of the other textile section, elastic sections permanently joined to and extending upwardly from the truncated upper ends of the textile sections and means at the

upper end of the said upwardly extending elastic sections to connect the same to corset appurtenances.

2. As a new and useful article of manufacture, a stocking supporter adapted to be worn about the stocking below the knee of the wearer, and including spaced textile sections with upwardly tapered and truncated upper portions, an elastic section interposed between and permanently connecting the adjacent ends of the lower portions of the textile sections, an elastic strap permanently joined to the outer end of the lower portion of one textile section, a buckle connected through a tape section with the outer end of the other textile section, elastic sections permanently joined to and extending upwardly from the truncated upper ends of the textile sections and means at the upper end of the said upwardly extending elastic sections to connect the same to corset appurtenances; one of the said upwardly extending elastic sections being equipped with a lateral subsection carrying fastening means to connect the upper portion of a stocking thereto.

CLARE MacDONALD SUPPLE.
